DESIGN FOR A SHOE TREE

Stefan W. Robitsek, New York, N. Y.

Application September 12, 1944, Serial No. 115,279

Term of patent 7 years

(Cl. D7—3)

To all whom it may concern:

Be it known that I, Stefan W. Robitsek, citizen of Austria, residing at New York, in the county of New York and State of New York, have invented a new, original, and ornamental Design for a Shoe Tree, of which the following is a specification, reference being had to the accompanying drawing, forming part thereof.

Fig. 1 is a side elevation of a shoe tree embodying my new design, and

Fig. 2 is a bottom view of the same.

My design for a shoe tree is characterized by the specific configuration of the outwardly extended tongue, the heel block and the screw rod, all in their relative positions as shown.

I claim:

The ornamental design for a shoe tree, as shown and described.

STEFAN W. ROBITSEK.
